Primary Examiner — Manpreet S Matharu*Assistant Examiner* — Yolanda Robinson(74) *Attorney, Agent, or Firm* — Maceiko IP(57) **CLAIM**

The ornamental design for an orthopedic clamp, as shown and described.

DESCRIPTION

FIG. 1 is a perspective view of a first embodiment of an orthopedic clamp.

FIG. 2 is a right-side view thereof;

FIG. 3 is a left side view thereof;

FIG. 4 is a bottom plan view thereof;

FIG. 5 is a top plan view thereof;

FIG. 6 is a front view thereof;

FIG. 7 is a back view thereof;

FIG. 8 is a perspective view of a second embodiment of an orthopedic clamp;

FIG. 9 is a right-side view thereof;

FIG. 10 is a left-side view thereof;

FIG. 11 is a bottom plan view thereof;

FIG. 12 is a top plan view thereof;

FIG. 13 is a front view thereof; and,

FIG. 14 is a back view thereof.

The broken lines shown in the orthopedic clamp are for portions that form no part of the claimed design.

1 Claim, 10 Drawing Sheets(56)
